UNITED STATES PATENT OFFICE.

WILLIAM T. INGRAM, OF RULETON, KANSAS.

INTERNAL-COMBUSTION ENGINE.

1,239,274.

Specification of Letters Patent.

Patented Sept. 4, 1917.

Application filed June 24, 1916. Serial No. 105,724

To all whom it may concern:

Be it known that I, WILLIAM T. INGRAM, a citizen of the United States, residing at Ruleton, in the county of Sherman and State 5 of Kansas, have invented certain new and useful Improvements in Internal-Combustion Engines, of which the following is a specification, reference being had to the accompanying drawings.

10 This invention is an internal combustion engine.

One object of this invention is to provide means to utilize the explosive pressure on two pistons operable within one cylinder.

15 Another object is to reduce the vibrations caused by the explosions.

A further object is to provide two pistons operable within one cylinder and connecting the pistons directly to the crank shaft in 0 such a manner that a turning effort will be produced by each piston.

25 A still further object is to provide an engine with a plurality of cylinders, each having two pistons operable therein, connecting one-half of the pistons by means of rods to the crank shaft and connecting the other half of the pistons by rods to yokes, which yokes are suitably connected to the crank shaft so that a synchronous movement of the 30 pistons operates to produce a continuous rotation of the shaft.

Broadly stated the invention comprises a crank shaft, a plurality of cylinders, each of the cylinders being provided with two 35 pistons operable therein, certain of the pistons being connected to the crank shaft by connecting rods, the rest of the pistons being connected in pairs by connecting rods to a plurality of spaced yokes, the yokes being 40 connected to the crank shaft by means of connecting and coupling rods, ports for said cylinders, connecting means adapted to fire the compressed fuel, a water jacket for each of the cylinders, and means to mount the 45 crank shaft and cylinders.

One practical form of the invention will be described and illustrated in the accompanying drawing, in which,

The figure is a vertical sectional view; 50 As shown in the figure, the engine is inclosed in a casing A. The engine comprises four cylinders indicated by the numerals 5, 6, 7 and 8. These cylinders are provided substantially mid-way between their ends 55 with suitable inlet ports 9, 10, 11 and 12 and with exhaust ports 13, 14, 15 and 16. Ex-

tending through the walls of each of the cylinders are the spark plugs 17, 18, 19 and 20.

Surrounding each of the cylinders are wa- 60 ter jackets B. These jackets are utilized for the purpose of keeping the several cylinders cool adjacent the point of explosion and where the hottest gases exist. As shown, these cylinders and their water jackets are 65 preferably cast in pairs. The cylinders are secured to the casing A by means of the channel or angle members 21, and 22 and they are spaced apart by means of the channel member 23. As shown, these several 70 angle members 21, 22 and 23 are bolted to the casing and to the several cylinders by means of the bolts 24. Each of these angle members carry at a predetermined point a removable bushing. As shown in the drawing, the channel members 21, 22 and 23 have positioned within them the bushings 25, 26, 27 and 28. These bushings also serve 75 as guide elements.

Disposed in the lower part of the casing, 80 is a crank shaft C which is provided with the usual cranks 29, 30, 31 and 32. These cranks may be of the usual type and form the construction as is customary in making crank shafts and they are preferably positioned so that the cranks 29 and 30 are displaced through one-hundred and eighty degrees with respect to the cranks 31 and 32. The cranks are provided with webs between which extend the crank pins. Dis- 85 posed upon this crank shaft are other cranks 33, 34, 35 and 36 which are so positioned or displaced from the other cranks that they may be connected suitably with pistons operable within the cylinders. This crank 90 shaft is adapted to rotate in suitable bearings 37 and 38, as shown in the figure.

Operable within the cylinders 5, 6, 7 and 8 are a plurality of pistons, two of which are provided for each one of the cylinders. 100 Within the cylinder 5, there are disposed the pistons 39 and 40, and within the cylinder 6 there are disposed the pistons 41 and 42, and within the cylinder 7 there are disposed the pistons 43 and 44, and within the cyl- 105 inder 8, there are the pistons 45 and 46. These pistons may be of any usual or cus- tomary type and are provided with suitable pins, one of which is indicated at 47.

This pin may be secured within the piston 110 by means of the set screws 48.

The connecting rods 49, 50, 51 and 52 are

connected to their respective crank pins disposed within the cranks 29, 30, 31 and 32. These crank pins may be formed as an integral part of the crank shaft and webs or they may be separately inserted therein and secured in any customary manner. The connecting rods 53, 54, 55 and 56 are connected to the pistons 39, 41, 43 and 45 in a similar manner to that connection described for the piston 42. The connecting rods 53 and 54 are suitably secured to a yoke 57. The securing means, as illustrated, comprises a threaded end for the connecting rod and the nuts 58. The connecting rods 55 and 56 are suitably connected to the yoke 59 by means of a threaded end and the nuts 60.

The yokes 57 and 59 are provided with suitable apertures adjacent their outer ends through which pass the coupling rods 61, 62, 63 and 64. The several ends of these rods are provided with screw threads and are adapted to coöperate by means of these threads with the nuts 65. The coupling rods 61, 62, 63 and 64 move within and are guided by the bushings 25, 26, 27 and 28. The other ends of these coupling rods 61, 62, 63 and 64 are provided with suitable forks 66, 67, 68 and 69. These forks are provided with suitable apertures through which the pins 70 pass.

The connecting rods 71, 72, 73 and 74 are provided at one end with a suitable hole to engage with the pins 70 which are disposed within the forks 66, 67, 68 and 69. These pins are used to connect the several coupling rods with their respective connecting rods. The other ends of the connecting rods 71, 72, 73 and 74 are provided with suitable bearings to coöperate with the crank pins formed in the cranks 33, 34, 35 and 36.

The upper ends of the cylinders are connected to the top of the crank piece by means of a web section 75. This web section is secured to this top by means of the bolts 76. A slot 77 is formed in each one of these web sections which is of sufficient width to permit the yokes 57 and 59 to freely move therein. These slots, however, may be made so that they provide bearing surfaces to coöperate with the yoke if so desired.

The crank shaft C may be supported intermediate of the bearings 37 and 38, as indicated at 78 and 79. These bearings 78 and 79 may be of the customary form and type and if desired, additional bearings may be utilized to better support the crank shaft. No particular means have been shown with respect to valve operation or the valves themselves as they are preferably standard types. No means are shown for circulating the water in the water jacket B but at the upper end of the water jacket, lying between the pairs of cylinders, are water spaces 80 and 81. The lower ends of the cylinders 65 may be supported in any usual or customary

way or they may extend free from the channel or angle members 21, 22 and 23, as shown.

In practical operation, both of the pistons operate to draw in the charge and compress it and after the explosion occurs, the pistons operate to force the exhaust gases out and thus very thoroughly scavenge the cylinder of the unburnt and other gases. The movement of the pistons, as for illustration the cylinders 5 and 6, is as follows: As the pistons are forced outwardly toward the end of the cylinders, a turning movement is communicated to the crank shaft by means of the pistons 40 and 42. The pistons 39 and 41 are also moving outwardly and operate on the yoke 57 which in turn is connected to the crank shaft by means of the coupling rods 61 and 62 and the connecting rods 71 and 72. Thus the pistons contribute to impart rotary motion to the crank shaft upon their movement. The cranks 33 and 34 are positioned either a little more or a little less than one-hundred and eighty degrees with respect to the cranks 29 and 30 and the cranks 35 and 36 are similarly positioned with respect to the cranks 31 and 32. It is preferable to fire the cylinders in a predetermined order which corresponds to firing cylinder 5, then 7, then 6, then 8.

Having thus described this invention, what is claimed is:—

1. In an internal combustion engine, a supporting frame including an upper transverse member, and vertical side members, a plurality of cylinders vertically disposed within the frame and having vertically slotted webs attached at their upper ends to said transverse member, spacing and supporting members disposed between the cylinders and the vertical side members and holding the cylinders in a vertical position, an upper and a lower piston in each cylinder, a crank shaft having a crank for each cylinder thereon, certain of the cranks being connected to the lower pistons, transversely extending yokes operatively connected to the upper pistons and extending through the slots in said webs, and connecting rods operatively connected to and extending between said yokes and certain cranks on the shaft.

2. In an internal combustion engine, a plurality of cylinders arranged in pairs and open at opposite ends, a pair of oppositely disposed pistons in each cylinder, intercommunicating water jackets on the cylinders of each pair of cylinders, each pair of cylinders having upwardly extended slotted webs, brackets connected to and spacing one pair of cylinders from the next adjacent pair, brackets connected to and supporting the end cylinders, a crank shaft having a crank for each cylinder, the cranks for one pair of cylinders extending in an opposite direction to the cranks of another pair of cylinders.

- ders, a yoke for each pair of cylinders extending through the corresponding slotted webs, a pair of cranks on the crank shaft for each yoke, the cranks for one yoke extending in a direction opposite to the cranks for the other yoke, guide rods extending downward from the ends of each yoke and having sliding engagement through the brackets, and connecting rods connecting the last named cranks to the guide rods, each pair of cylinders having intercommunicating water jackets, the walls of said water jackets of each pair extending between and connecting the pair of cylinders and each cylinder at its middle having intake and outlet ports.
3. In an internal combustion engine, a casing comprising upper, lower and side walls, a crank shaft passing through the lower end of the casing, a plurality of interconnected pairs of cylinders disposed in said casing and having upper and lower ends, each pair of cylinders having upwardly extending webs vertically slotted and attached at their upper ends to the upper wall of the casing, perforated brackets supporting the cylinders from the end walls of the casing and spacing one pair of cylinders from the other, upper and lower pistons disposed in each cylinder, the lower pistons being connected to cranks on the crank shaft, the cranks of one pair of pistons being disposed in a direction opposite to the cranks of the other pair of pistons, a yoke for each pair of cylinders passing through the slotted webs thereof and operatively connected to the upper pistons, a pair of cranks on the crank shaft for each yoke, the cranks for one yoke being disposed in an opposite direction to the cranks for the other yoke, guide rods connected to said yoke, cranks passing through the perforations in the brackets, and connecting rods operatively connected to the yoke, cranks and to the guide rods, each pair of cylinders being formed with surrounding intercommunicating water jackets, the webs of the water jacket between each pair of cylinders being connected to and bracing the cylinders from each other.

In testimony whereof I hereunto affix my signature in the presence of two witnesses.
